UNITED STATES PATENT OFFICE.

HORACE M. CAPRON, OF CHICAGO, ILLINOIS, ASSIGNOR, BY MESNE ASSIGNMENTS, TO EQUIPMENT CORPORATION OF AMERICA, OF CHICAGO, ILLINOIS, A CORPORATION OF DELAWARE.

DESIGN FOR AN INDUSTRIAL TRACTOR.

53,627.

Specification for Design.

Patented July 22, 1919.

Application filed March 6, 1918. Serial No. 220,874. Term of patent 14 years.

To all whom it may concern:

Be it known that I, HORACE M. CAPRON, a citizen of the United States, residing at Chicago, in the county of Cook and State of Illinois, have invented a new, original, and ornamental Design for Industrial Tractors, of which the following is a specification, reference being had to the accompanying drawings, forming part thereof.

The figure is a perspective view of an industrial tractor, embodying my new design.

I claim:

The ornamental design for an industrial tractor, as shown.

HORACE M. CAPRON.
